Andrew W. Chu(57) **CLAIM**

The ornamental design for a carbon infrared space heater as shown and described.

DESCRIPTION

FIG. 1 is a front elevation view of the carbon infrared space heater according to my design;

FIG. 2 is a back elevation view thereof;

FIG. 3 is an end elevation view thereof;

FIG. 4 is an opposite end elevation view thereof;

FIG. 5 is a side elevation view thereof;

FIG. 6 is an opposite side elevation view thereof; and,

FIG. 7 is an upper perspective view thereof.

The broken lines shown in the drawings are included for the purpose of illustrating portions of the carbon infrared space heater that form no part of the claimed design.
